(57) **CLAIM**

The ornamental design for a support for clock, as shown and described.

DESCRIPTION

FIG. 1 is a front view of the support for clock showing the present design,

FIG. 2 is a side view thereof; and,

FIG. 3 is a perspective view thereof.

The broken lines in FIGS. 1 and 3 are used to show portions of the support for clock that do not form part of the claimed design.

1 Claim, 1 Drawing Sheet

FIG. 1

FIG. 2

FIG. 3
